UNITED STATES PATENT OFFICE.

CHARLES RUFFLY, OF RIXHEIM, GERMANY.

DESIGN FOR A BORDER FOR WALL-PAPER.

SPECIFICATION forming part of Design No. 29,955, dated January 3, 1899.

Application filed December 6, 1898. Serial No. 698,478. Term of patent 7 years.

To all whom it may concern:

Be it known that I, CHARLES RUFFLY, a subject of the Emperor of Germany, residing at Rixheim, Alsace, Germany, have invented and produced a new and original Design for a Border for Wall-Paper, of which the following is a specification, reference being had to the accompanying drawing, forming a part thereof, which represents a plan view of a section of border embodying the features of my design.

The leading feature of the design is the representation of a festooned fabric A and bunches of flowers B at the ends of the fes-

toon. In detail the bunches of flowers conceal the ends of the festooned fabric, and a dado C apparently supports the festooned fabric, the dado being in the form of a longitudinal panel ornamented by sprays of laurel tied together.

I claim—

The design for a border for wall-paper herein shown and described.

CHARLES RUFFLY.
